SIDE OPENING MILK COOLER

Raymond D. Pusey, Smyrna, Del., assignor to
 Wilson Refrigeration, Inc., Smyrna, Del., a corporation of Delaware

Application October 9, 1950, Serial No. 189,219

2 Claims. (Cl. 62—141)

1

This invention relates to milk coolers, and the principal object of the invention is to provide a cooler of generally improved structural form and functional characteristics.

A more specific object of the invention is to provide a milk cooler comprising the conventional cabinet, water cooling, and water distributing and circulating means wherein access to the cabinet for insertion and removal of the milk cans is afforded by way of an opening in a side wall of the cabinet, said cooling, distributing and circulating means being constructed and being arranged within the cabinet in a manner best adapted to the side wall access design in both the structural and functional respects.

Another object of the invention is to provide a milk cooler of the side opening type wherein the cooling device takes the form of a self-contained refrigeration unit which is installed in the cooler assembly by way of an opening in the top wall of the cabinet, said unit being supported on the said top wall and being readily detachable by a simple lifting operation from the cabinet for repair, cleaning, or replacement.

Another object of the invention is to provide a milk cooler of the stated type wherein the means for circulating the water in the cabinet takes the form of a self-contained pump unit installed in the cabinet by way of an opening in the top wall thereof and supported on the latter in a manner affording ready removal of the unit by a simple lifting operation for repair, cleaning, or replacement.

Still another object of the invention is to provide a milk cooler wherein the water or other liquid cooling medium is distributed over the surfaces of the milk cans by way of a duct system which is removable as a unit from the cabinet for cleaning, repair or replacement.

A still further object of the invention is to provide a milk cooler wherein the means for supporting the milk cans in the cabinet takes the form of a detachable rack readily removable from the cabinet through the side opening for cleaning, repair, or replacement.

Another object is to provide a milk cooler of the stated class wherein the inner functional elements including the cooling means, circulating and distributing means, and the milk can support elements are readily removable as units from the cabinet for cleaning or other purposes, and wherein removal of the said units leaves the inner surfaces of the cabinet unobstructed and readily accessible for thorough cleaning, said cooler being thereby highly susceptible to maintenance in a sanitary condition.

A still further object is to provide a milk cooler comprising readily detachable cooling and circulating units of the character described above and wherein temperature controls for the liquid

cooling medium and for the milk can storage or cooling compartment are associated as integral parts thereof with the cooling and circulating units respectively.

5 A broader object is to provide a milk cooler having separate temperature control means for the liquid cooling medium and the storage compartment, said control means operating cooperatively to maintain substantially constant temperatures in the said medium and in the compartment.

The invention contemplates also provision in the cabinet of a large vertical reservoir in which the cooling element of the refrigerating unit is housed for intimate contact with the liquid cooling medium, said reservoir affording a large volume of refrigerated liquid in relation to the can storage capacity of the cabinet.

15 The invention resides further in certain structural details hereinafter described and illustrated in the attached drawings, wherein:

Fig. 1 is a view in perspective of a milk cooler made in accordance with the invention;

Fig. 2 is a vertical sectional view on the line 25 2—2, Fig. 1;

Fig. 3 is a horizontal sectional view on line 3—3, Fig. 1;

30 Figs. 4 and 5 are views in perspective of the refrigeration and water circulating units respectively;

Fig. 6 is a view in perspective of a preferred form of water distributing duct system detached from the cabinet; and,

Fig. 7 is a view in perspective of the milk can supporting rack also removed from the cabinet.

35 With reference to the drawings, the milk cooler therein illustrated comprises a rectangular cabinet 1, having an opening 2 in the front wall thereof which is normally closed by a door 3 hinged to the cabinet at one side of the opening. As shown in Fig. 1, the door 3 is provided with the usual sealing gasket 4, and on the inner side and at the lower part thereof with a wiper gasket 5 which with the positive seal afforded by the gasket 4 effectively precludes escape of liquid through the door.

40 The inside of the cabinet is divided by a partition 6 into compartments 7 and 8, the major compartment 7 being designed for storage of the milk cans containing the milk to be cooled, and the minor compartment 8 constituting a reservoir for the water or other cooling medium which after being refrigerated in the compartment 8 is distributed over the surfaces of the milk cans located in the storage compartment 7 in a manner hereinafter described.

45 It will be noted that the milk cans 9, indicated in broken lines in Fig. 1, are supported in the cabinet upon a rack 11 which is best illustrated 50 in Fig. 6, this rack consisting of longitudinal base

members 12 and 13 in the form of channels, and transverse angle bars 14, 15, 16 and 17 which are secured to the tops of the channels 12 and 13 and which are arranged so as to form in effect two sets of rails spaced in conformity with the diameter of the can so that the latter may seat thereon and be confined to the rails by the upstanding flanges of the angle bars. In assembly, this rack is supported in the bottom of the compartment 7 of the cabinet with the horizontal flange or the can-supporting rails approximately even with the lower edge of the opening 2 so that the cans may be readily deposited on the front ends of the rails through said opening and then pushed rearwardly into the cabinet.

Mounted on the top wall 21 of the cabinet above the reservoir chamber 8 is a refrigerating unit which comprises a depending cooling coil 22, a hermetically sealed compressor unit 23, condenser 24, and a fan 25 in operative association with the evaporator. These elements are mounted on a base 26 which seats upon the top of the cabinet over an opening 27 through which the cooling coil 22 extends into the chamber 8, the base 26 forming a cover for the opening 27. Preferably the unit 23 is controlled automatically by a thermostat 61 which is responsive to the temperature produced by the refrigerating unit. In this way the amount of ice formed on the convolutions of the coil 22 may be accurately regulated.

This construction provides a complete self-contained drop-in refrigeration unit with hermetically sealed condensing unit which is readily installed simply by dropping the coil 22 through the opening provided in the top of the cabinet.

This feature permits the self-contained refrigerating unit to be easily removed from the cabinet merely by lifting the base 26 upwardly until the coil is freed from the chamber 8 thereby rendering it accessible for cleaning and for service or replacement of the refrigerating unit.

Circulation of the water from the chamber 8 over the surfaces of the cans in the storage compartment 7 is effected by overflow from the said chamber into a distributing duct system, best illustrated in Fig. 6. As therein illustrated this system consists of a central channel 31 to each of the opposite ends and the center of which, respectively, are suitably secured in depending position narrow open-top troughs 32, 33 and 34, said troughs extending transversely of and to both sides of the channel. The bottom of the channel 31 is provided with apertures 35, 36, and 37 which open into the tops of the troughs.

Each of the troughs 32 and 33 is provided in the side face thereof, which confronts the trough 34, with a series of small ports designated by the reference numeral 38, and similar ports 39 are provided in both side faces of the trough 34. As shown in Figs. 1 and 2, this distributing duct structure constitutes a unitary structure which is detachably supported in the top of the chamber 1 of the cabinet on transverse flange rails 41 and 42 so that the channel 31 extends substantially central of the chamber from one side to the other, and the troughs 32, 33 and 34 occupy positions adjacent and on opposite sides of the cans supported on the rack 11. The outer face of the trough 32 abuts the face of the partition 6, and the partition is provided with a weir 30 in its upper edge which overhangs the proximate end of the channel 31. When the water level in the compartment 8 reaches the bottom of

the weir 30, refrigerated water will flow from the chamber 8 into the channel, will pass through the ports 35, 36 and 37 into the troughs 32, 33 and 34 and will flow outwardly in a plurality of streams through the ports 38 and 39 against the necks and shoulders of the cans below the caps and flow downwardly over the side surfaces of the cans 9 supported in the chamber 1 as previously described. The water then collects in the bottom of the chamber 7 below the can-supporting rack 11 and will be pumped from this area, by means described below, into the chamber 8, this circulation of the water in the cabinet continuing uninterruptedly for such time as may be required to reduce the temperature of the milk in the cans to the desired extent.

The circulation of the water described above is effected through the medium of a pump unit designated generally by the reference numeral 45. This unit comprises an electric motor 46 mounted on a plate 47 and operatively connected with a suitable impeller mounted in a casing 48 at the lower end of a tubular housing 49 depending from the underside of the plate 47. A discharge port 25 of the impeller chamber is connected to the lower end of an upright duct 51 which extends in parallel relation with the tubular housing 49 and is provided at its upper end with a U-fitting 52. The duct 51 includes two separate pipe sections, 53 and 54 respectively, which are connected by a flexible tube 55, this affording adjustment of the length of the duct 51 as may be required.

Operation of the pump motor 46 is controlled automatically by a thermostat 62 which is responsive to the temperature in the storage compartment 7 so that the circulation of water is effected as required to maintain the desired milk cooling and storage temperature in the compartment.

This pump unit is installed in the cabinet through an opening 56 in the top wall of the latter. The plate 47 seats upon the top wall 21 of the cabinet and overlies and normally closes the opening 56, the tubular casing 49 extending 45 downwardly through the opening into the chamber 7 at the forward offset corner of the latter and adjoining the partition 6. The impeller casing 48 lies at the bottom of the chamber 7 and the duct 51 extends upwardly at the face of the partition 6 and over the top of the latter, the U-shaped fitting at the top of the duct 51 directing the stream of water downwardly toward the bottom of chamber 8 and agitating the water in the reservoir. Like the refrigerating unit described above, the pump 45 also constitutes a self-contained unit which, as such, may be installed and removed in and from the cabinet 1 in obvious manner.

The general mode of operation of the cooler 60 will be readily understood from the foregoing description. It is reiterated, however, that both the cooling unit and the pump unit is regulated in its operations by a thermostat which constitutes an integral element of the unit.

These thermostatic controls serve to maintain an adequate ice reserve in the compartment 8 to meet maximum and minimum temperature requirements determined by an adjustable temperature control on the cooling unit, and to insure 65 safe storage temperatures after initial cooling of the milk in the storage compartment.

It will be noted that the cooler exhibits both simplicity of form and high functional efficiency, the assembly of the functional elements of the 70 cooler in the cabinet being effected with a mini-

imum of complication and being readily accessible by merely lifting from the cabinet for cleaning, adjustment, repair or replacement. The readily removable self-contained refrigeration and pump units afford a simple means for quick replacement of these primary operating parts so that the cooler may be maintained in continuous and substantially uninterrupted operation. The relatively large capacity of the chamber 8 with respect to the storage capacity of the chamber 7 insures an adequate supply of refrigerated water for continuous distribution over the milk cans with consequent relatively rapid reduction in the milk temperature. The ready removability of the "lift out" refrigerating and pump units and of the duct system and can rack, also provides for rapid and efficient cleaning of these parts and of the whole cabinet interior, so that the cooler may be maintained economically in completely sanitary condition. As set forth above, the novel temperature control system insures that the milk temperature will not rise during the storage periods after the quick cooling operation has been completed and before the milk is removed for distribution.

I claim:

1. In a milk cooler a cabinet having top, bottom and side walls and an upright partition dividing the interior thereof into major and minor compartments, an opening in a side wall of the cabinet affording access to the major compartment for insertion and removal of milk cans, said opening being spaced from the bottom of the interior of said major compartment so as to form within said compartment below said opening a water-tight reservoir, a door for said opening, an opening in the top of the cabinet above the minor

compartment, a self-contained refrigerating unit mounted on the top wall at said opening and including a cooling element depending through the opening into the minor compartment, said unit being removable from the cabinet, and means for circulating a liquid cooling medium through the compartments successively and over the surfaces of the milk cans inserted in the major compartment, said circulating means including a distributing duct system in the top of the major compartment communicating with the upper part of the minor compartment so as to receive water from the latter by overflow, and means for transferring water from the reservoir in the bottom of the major compartment to the minor compartment.

2. A milk cooler according to claim 1 wherein said water transfer means comprises a self-contained pump unit mounted in the top wall of the cabinet and extending downwardly to the bottom of the major compartment, said pump unit being removable from the cabinet independently of the refrigerating unit.
